ROLLER CLIP BOARD

Robert H. Ensign, Bronxville, and Alben G. Jackson, New York, N.Y., assignors, by mesne assignments, to Montag, Incorporated, Atlanta, Ga., a corporation of Ohio

Filed Mar. 1, 1961, Ser. No. 92,583
1 Claim. (Cl. 129—23)

This invention relates to a holder structure for loose-leaf filler paper. More particularly, the invention is concerned with a loose-leaf binder for such filler sheets having at least a pair of perforations provided adjacent one edge, which perforations are adapted to be engaged by a suitable holding means such as split rings, covered pins, etc., to retain the loose-leaf sheets within the binder.

The invention to be described herein is concerned with a novel and unique loose-leaf holder of the type wherein a support is provided for the underside of the filler paper which in effect renders the structure a portable desk and wherein the paper may be covered and protected during such time that the writing surface is not in use.

Structures of the general type are known in the art and are generally of the so-called "clip board" type wherein the edge of the supply of paper is engaged by a spring clip means and held in place on the supporting board structure. While such devices have utility, one main objection is the fact that no means are provided wherein the writing surface whether used or fresh, can be protected from smudging or dirt such as will occur or accumulate when these devices are used in industrial plants or by contractors, or for the recording of data, such as research data, etc.

Accordingly, an object of the invention is to provide a novel loose-leaf binder.

A further object of the invention is to produce a loose-leaf binder which may be used under a variety of circumstances which will maintain the writing surface of the filler paper clean and in usable and legible condition.

An additional object of the invention is to provide a filler paper binder wherein the surface of the filler paper is protected by a unique pull down cover.

Still another object of the invention is to provide a unique pull down cover for loose-leaf binders wherein the cover and binder structure are comprised of rugged, wear resistant materials.

An additional object of the invention is to provide a cover for loose-leaf binders which is conveniently used and which may be manufactured economically.

These and other objects of the invention, not specifically referred to, inherent in the invention may be accomplished by providing a base member for supporting the full extent of the undersurface of filler paper attached thereto; releasable means for maintaining said sheets positioned on said base; cover means for overlying the exposed top surface of the filler paper, said means comprising a roller mounted on said base, a flexible protective sheet attached to the roller; a resilient biasing means acting on the roller whereby said cover will be rolled upon said roller when not in use and may be unrolled from said roller when in use and means for securing the flexible cover in its use position.

2

Having thus defined the area of invention in general terms, the device will be described in detail, reference being made to the attached drawing, wherein

FIG. 1 is a top plan view of the device comprising the instant invention,

FIG. 2 is an enlarged elevational view taken along the line 2—2 of FIG. 1, and rotated 90° counterclockwise,

FIG. 3 is a sectional view taken along the line 3—3 of FIG. 2,

FIG. 4 is an enlarged view of two plug elements utilized in the rewinding mechanism, and

FIG. 5 is an enlarged view showing a preferred means for attaching the flexible cover to the roll mechanism.

Considering first FIG. 1, it will be seen that the device consists of a base member 1 which forms a support for the filler insert which is comprised of superposed sheets of paper 3, having at least a pair of spaced apertures 4, 4', provided adjacent one edge, in this case the top edge. The base member 1 is provided with a pair of upturned, parallel edge members 5 and 6. These edge members are relatively shallow in a generally perpendicular direction to the base 1 but gradually deepen toward the top of the base, finally terminating at the top edge of the binder in a pair of wing-like extensions 7 and 8.

The base is further provided with at least a pair of spaced pins 9 and 10 which pins are adapted to engage the apertures 4, 4' provided adjacent the edge of filler papers. It will be appreciated that the filler, comprised of the superposed sheets 3, is inserted over the pins 9 and 10 and held in the proper position on the base 1 by means of the pins. It will also be evident that some means should be provided to maintain the sheets of paper emplaced on the pins such that they cannot accidentally dislodge or be lost.

Returning now to the wing-like extensions 7 and 8 illustrated in FIGS. 1 and 2, it will be seen that these members serve as supports for a closure member 12 comprised essentially of a rectangular plate having trunnions 14 and 16 journaled within suitable apertures provided in the extensions 7 and 8.

The cover member 12, as seen in section in FIG. 2, is of substantial thickness and is provided with a pair of spaced transversely aligned recesses 15, 15' (only one illustrated) which are adapted to meet with and engage the tops of the pins 9 and 10. In addition it will be noted that the trunnions 14 and 16 are disposed somewhat below a medium plane passing through the longitudinal center of cover member 12 such that the rear edge thereof swings through an arc if the cover is swung from a position overlying pins 9 and 10 to a position away from these pins. This edge 12 is so contoured as to define an over center cam which extends transversely across the entire width of the cover and is in engagement with a resilient upstanding member 20 which member is adapted to bear against cam surfaced edge 30 defined on the rear edge of the cover 12. Thus as will be apparent, the resilient member 20 will bear against the cam surface 30 to lock the cover in place against the tops of the pins when the cover member is positioned over the pins. Also when the cover member is pivoted away from the pins the resilient member 20 will give, enabling cam surface 30 to pass to "over" center

position maintaining the cover out of engagement with the pins 9 and 10 such that the paper sheets 3 comprising the filler package may be engaged or disengaged from the pins at will.

Considering now FIGS. 2 and 3 it will be seen that the rear most portions of the wing-like extensions 7 and 8 are connected transversally by a generally inverted L shaped housing 24 which has one leg 26 extending downwardly between extensions to define a rear wall between the extensions; the other leg 28 of which is perpendicular thereto, slightly arched, and extends from the rear wall 24 toward the resilient member 20. The terminal edge 32 of this leg of housing 24 is spaced from the terminal edge of the resilient member 20 to define therewith a longitudinal slot extending transversally across the base and being disposed parallel to the upper edge of the sheets 3 impaled on the pins 9 and 10.

That portion of each of the extensions 7 and 8 disposed beneath the housing 24 is provided with further apertures 36 and 38, respectively, which apertures are located in transversally spaced coaxially aligned relation. The aperture 36 is generally circular in configuration while aperture 38 is rectangular in configuration. Each of the apertures 36 and 38 receives a plug member 50 and 60 respectively, these being illustrated in FIG. 4.

The plug 50 consists essentially of a generally cylindrical portion 42, a head 46 and cylindrical boss 48 which boss is adapted to fit within the aperture 36 such that the plug 50 will rotate therein. The head 46 of course bears against the side of wing 7.

The plug 60, on the other hand, includes a similar cylindrical portion 49 and head 52, but rather than a cylindrical boss, it is provided with a generally rectangular boss 54 which is adapted to engage the rectangularly configured aperture 38 such that when the head 52 bears against the extension 8 this plug 60 is held in non-rotatable relation with respect thereto.

Each of the cylindrical portions 42 and 49, plugs 50 and 60 respectively, are provided with a slot and groove arrangement 56, 56' so contoured as to be able to engage the end loops 72, 72' of a coil spring 70 which is stretched between the plugs and confined within the housing 24 as shown in FIG. 3. The spring 70 is in turn surrounded by a roller 74 provided at one end with a pair of diametrically aligned slots 75. The opposite end of the roller 74 is plain and will bear against the inner surfaces of the extension 8. The slotted end of the roller 74 is adapted to engage a pair of diametrically aligned tongue-like elements 76 which are formed on the outer surface of the cylindrical portion 42 of plug 50 such that the plug 50 will be caused to rotate as the roller 74 is caused to rotate. It will be apparent from the described and illustrated structure that rotation of a roller 74 in a clockwise direction (as illustrated by the arrow in FIG. 2) will cause the spring 70 to build up a resilient force tending to rewind the roller in a counter-clockwise direction.

Having one edge thereof fixed to the roller any suitable means such as adhesive or by the means illustrated in FIG. 5, is a piece of flexible plastic or similar substance in the form of a sheet 80. The configuration and size of this sheet 80 is such that it will, when unwrapped from the roller 74, cover the entire exposed writing surface of the paper sheets 3 emplaced on the base 1. Preferably the lower edge of base 1 is provided with an upstanding tongue 90. The free edge of the flexible cover 80 is so formed as to receive a rod-like member 82 having a U shaped intermediate portion 84 which is adapted to engage the tongue 90 to keep the cover from rewinding or roller 74 when the cover sheet 80 is serving its protective function.

It will be noted that the diameter of the rod 82 is such that it is greater than the width of the slot defined between the terminal edge 32 of the aforesaid housing mem-

ber 24 and either the cam surface 30 of closure member 18 or the terminal edge of the flexible member 20. Thus it will be seen that while the normal condition of the resilient spring 70 will be such as to keep the cover member 80 wrapped upon the revolving roller 74. The terminal edge of the cover member 80 which surrounds the rod 82 will thus be prevented from slipping beneath the housing 24. The loop portion 84 of rod 82 serves as a manual grasping means wherein the cover 80 may be pulled downwardly over the surface of the paper, the loop then being engageable with the tongue 90 to maintain the cover in an extended, protective position.

As we stated, the cover 80 may be fixed to the roller 74 by means other than an adhesive. Such an arrangement is illustrated in FIG. 5 wherein the roller 74 is provided with a slot 78 which receives a bead 81 formed on the edge of the cover 80. It will be appreciated that a variety of means may be employed to form the bead 81. Where the cover is a flexible vinyl plastic, a preferred material, the bead may be formed by applying heat to the edge of the cover and thereafter molding the bead to the desired size.

It will be noted that in the description above, the invention has been described in terms of a structure wherein the paper holding means and the cover actuating mechanism are disposed across the top edge of the supporting base 1. It is quite obvious that the same instrumentality could be disposed along the longer side of the base 1 should this arrangement be desirable. It will be further appreciated that this and other changes may be made in view of the disclosure wherein all of which are within the spirit and scope of the invention which is limited only as defined in the following claim.

Wherein what is claimed is:

35 A binder for holding a stack of paper sheets each having a pair of aligned holes cut near the top edge thereof, comprising a flat base member for supporting the sheets throughout their length and width, a pair of upstanding posts on said base member extending through the holes in the sheets for holding the sheets against movement in a plane parallel to said base member, side walls on each side of said base member projecting perpendicularly to said base member to protect the side edges of the sheets, a resilient end wall on one end of said base member extending perpendicularly upwardly therefrom and being connected at the opposite ends thereof to said side walls, a closure member extending across the base member above said posts and adjacent said end wall for engaging the tops of said posts to hold the sheets thereon, pivot means on each end of said closure member for securing the ends of said closure member to the associated said side wall for pivotal movement between a first position wherein said closure member engages said posts and a second position wherein said closure member is spaced from said posts to facilitate removal of the sheets therefrom, said closure member having two adjacent and parallel surfaces both of which are parallel to said resilient end wall, one of said surfaces being in intimate contact with said end wall when said closure member is in said first position for holding said closure member in this position and the other of said surfaces being in intimate contact with said end wall when said closure member is in said second position for maintaining said closure member in this position, said end wall being sufficiently resilient to permit movement of said closure member between said first and second positions, said side walls having extensions which project beyond said end walls, roller means having its opposite end connected to and supported by said extensions, a retractable protective sheet carried by said roller means and extensible into an overlying protective relation with said closure member and the paper sheets, one edge of said cover sheet being fixed to said roller means, resilient means disposed internally of said roller means and connected thereto and to said extension for biasing said roller means to reel said

cover sheet upon its outer surface, said resilient means including a coil spring disposed internally of and extending through said roller means, means connecting one end of said spring to one of said extensions and the opposite end to said roller means, means carried by the opposite free end of said cover sheet and engageable with said base for maintaining said cover sheet extended over the paper sheets, and housing means connected to said extensions and extending across the width of said base member for protecting said roller and defining with said end wall a slot through which said cover sheet passes.
